UNITED STATES PATENT OFFICE.

ALFRED WEBER, OF NEW YORK, N. Y.

DESIGN FOR A LANTERN.

Application filed May 12, 1927. Serial No. 21,946. Term of patent 3½ years.

To all whom it may concern:

Be it known that I, ALFRED WEBER, a citizen of Austria, residing at New York, in the county of New York and State of New York, have invented a new, original, and ornamental Design for a Lantern, of which the following is a specification, reference being had to the accompanying drawing, forming part thereof.

The figure is a side elevational view of a lantern, showing my new design.

I claim:

The ornamental design for a lantern, as shown.

ALFRED WEBER.
